UNITED STATES PATENT OFFICE.

WILBUR G. LAIRD, OF NEW YORK, N. Y.

STORAGE APPARATUS.

Application filed March 31, 1923. Serial No. 628,960.

The present invention relates to a storage apparatus and, more particularly, to a tank in which gas and volatile or inflammable liquids may be stored without danger of fires or of exposing the stored liquid to the atmosphere.

Gas holders or tanks require a large liquid storage tank for holding water serving as a liquid seal into which the lower edges of the bell or lifts are immersed to seal the interior of the bell from communication with the atmosphere. The construction of gas holders heretofore used does not permit the storage of volatile, inflammable liquids, such as gasoline, kerosene or petroleum, since, as the bell or lifts rise and fall, they carry on their outer surface a film of the liquid in the liquid seal tank which would evaporate and thus create an explosive or inflammable atmosphere about the tank, as well as causing a considerable loss of liquid. Nor is the liquid seal tank, as heretofore constructed, suitable for the storage of heavy, viscous, liquids, such as coal tar, as a coating of the heavy residues would accumulate on the outer surface of the bell and lifts and thus create a very disagreeable situation.

These obstacles are overcome in the present invention, in which a storage space entirely protected from contact with the outer atmosphere and with the outer surface of the gas bell and lifts is obtained at a very small cost. Other aims of the invention are to provide a storage apparatus having an inner liquid storage chamber or reservoir and an outer water seal in which a very thin, light weight, dividing wall may be employed and to provide a storage apparatus in which the hydrostatic pressures of the water seal and of the stored liquid on this dividing wall are partly balanced. Further objects and features of the invention are, to provide, in storage means of the above type, devices for preventing the stored liquid from flooding the water seal and for indicating the quantity of liquid stored.

With these and other objects in view the invention comprises the apparatus and structure described and set forth in the following specification and claims.

The various features of the invention are illustrated in the accompanying drawings in which:

Fig. 1 is a vertical sectional view of a gas and liquid storage apparatus for liquids

specifically lighter than water, the apparatus being illustrated diagrammatically and guides, supporting elements and details of construction being omitted for the sake of simplicity and clearness, and,

Fig. 2 is a similar vertical sectional view of a gas and liquid storage apparatus for liquids heavier than water.

In the present invention, the liquid tank in which the gas holder is sealed is divided by a suitable partition wall into an outer liquid seal compartment for water or other suitable sealing liquid and an inner liquid storage compartment. Each of these compartments is kept filled to an approximately constant level so that the volume of the gas space is not affected by the quantity of stored liquid in the tank. For this purpose, the compartments communicate with each other and are so arranged that in withdrawing the stored liquid, the liquid is displaced by the admission of water or sealing liquid into a draw-off pipe and when being refilled it displaces the displacing water until the capacity of the storage compartment is reached. The levels of the liquid in the compartments do not change materially in these operations and the overflow of storage liquid into the sealing compartment is positively prevented. As the hydrostatic pressures on opposite sides of the dividing wall or partition are approximately balanced, this partition wall may be constructed of a very thin, light material.

Referring more particularly to the accompanying drawings, the invention is illustrated as applied to a gas holder of the usual construction, having a liquid seal tank 10, in which dips a gas bell or enclosing cover, a bell consisting of a lift 12 and a bell 14 being illustrated by way of example. A gas intake pipe 16 and an outtake pipe 18 of the usual type are also provided.

In the embodiment of the invention, the tank 10 is divided by a partition wall 20, concentric with and spaced from the vertical wall of the tank 10, into a central storage compartment 22 and a surrounding, annular, sealing compartment 24. In Fig. 1 is illustrated an arrangement of the apparatus for storing liquids specifically lighter than the sealing water and in Fig. 2 an arrangement for storing liquids specifically heavier than the sealing water.

In the embodiment of the invention il-

lustrated in Fig. 1, the wall 20 is supported, by suitable supports not shown, at a short distance above the bottom of the tank 10 to provide a passage 26 between the lower portions of the compartments 22 and 24. In filling the tank with sealing water, the water is supplied through a pipe 28 which has a vertical portion 30 extending up through the tank and opening at a level 32 even with that to be maintained in the water seal compartment. The water supplied through the pipe 30 sinks down through a surrounding pipe 34 to the bottom portion of the tank and rises until the desired level is reached in the sealing compartment 24. To prevent the water from being projected over the top of the pipe 34 this pipe may be enlarged at its upper end as at 36 and provided with a deflecting baffle 38.

The light liquid to be stored, such as gasoline, kerosene or petroleum, is supplied through a pipe 40 having a vertical portion 42 extending upwardly in the compartment 22 to a level 44 to which the lighter liquid is to be filled. The level 44 is higher than the level 32 by a distance corresponding to the difference in densities between the liquid and water above a level slightly higher than the bottom of the wall 20, and approximately even with the bottom of the pipe 34. The lighter liquid displaces the water in the compartment 22 into the pipe 34 through which it rises until it reaches the level 32 and overflows thru the pipes 30 and 28. Since the level 32 of the outlet of the pipe 30 is lower than the level 44 at which the lighter liquid enters, the displacement and overflow of water thru the pipe 30 will prevent the liquid level from rising above the level 44. When the dividing surface 46 between the liquid and water in the compartment 22 reaches the level of the bottom opening 48 of the pipe 34, the hydrostatic pressure of the liquid from the level of the opening 48 to the level 44 will just balance the hydrostatic pressure within the pipe 34. Any additional liquid admitted will, however, flow under the lower edge of the pipe 34 and escape through the overflow pipe 30. By placing the level of the opening 48 above the lower edge of the wall 20, all danger of the bottom 46 of the liquid sinking below the lower edge of the partition and of the liquid escaping through the opening 26 into the compartment 24 is avoided.

To withdraw liquid from the storage compartment 22, water is supplied through the pipe 28-30 and sinking downwardly through the pipe 34 enters the lower portion of the compartment and displaces the stored liquid upwardly until it overflows through the pipe 42. This may be continued until the upper level of the water reaches the

outlet level 44 of the pipe 42 at which point all of the stored liquid will have been withdrawn from the tank.

During this displacement of the stored liquid, the level 32 will rise proportionately with the displacement of the stored liquid and will reach the level 44 when the tank is empty of the lighter liquid. The level 32 of the water in the compartment 24 may be conveniently measured by means of a water gauge 50 attached to the side wall of the tank 10 at the proper height and through this arrangement the quantity of liquid stored in the compartment 22 may be readily determined.

In the arrangement illustrated in Fig. 2 for the storage of liquids heavier than the water used as a sealing liquid, the partition wall 20 rests on the bottom of the tank 10 forming a liquid tight closure therewith and is of a less height than the level 32 of the sealing liquid. The sealing liquid may thereby flow over the top edge of the wall 20 and maintain the compartment 22 always filled with liquid. The water supply and overflow pipe 30 is extended up above the top of the wall 20 to the level 32 and the surrounding pipe 34 is omitted inasmuch as the water is in this case supplied to the upper body of liquid.

The tar or heavy liquid supply and overflow pipe 42 extends to a level below the upper edge of the wall 20 and even with the level 44 of the heavy, stored liquid when the apparatus is filled to capacity. The pipe 42 is surrounded by a pipe 52 having a lower opening 54 immediately above the bottom of the tank 10 and having a function somewhat similar to that of pipe 34 of Fig. 1. In filling the compartment 22 with the heavy liquid, the liquid is supplied through the pipe 42 and sinks downwardly through the pipe 52. The liquid passes downwardly through the opening 54, spreads throughout the lower part of the compartment 22 and displaces the superjacent water into the pipe 30 which now acts as an overflow pipe. When stored liquid is to be withdrawn, water is supplied through the pipe 30, displacing the heavier liquid upwardly through the pipe 52 from which it overflows through the overflow pipe 42 and is withdrawn. In this arrangement the weight or hydrostatic pressure at the bottom of the compartment 22 will indicate the height to which the compartment is filled with the heavier liquid. This pressure may be measured in any suitable manner.

In the embodiments of the invention described above the hydrostatic pressures on opposite sides of the partition wall 20 are balanced at the bottom of the wall and are partly balanced throughout the greater part of the upper portion of the wall, the differ-

ence in the pressures being limited to the hydrostatic pressure between the levels 32 and 44. Accordingly, a very much lighter wall may be employed than if the pressures were not balanced.

Through this invention, also, the stored liquid is perfectly sealed from the atmosphere, no air being drawn into the tank when liquid is being withdrawn and no gas being expelled when the tank is being filled. A very safe and fire proof storage is thus provided and the invention may be applied where the primary purpose is the safe storage of liquids as well as the storage of gas.

15 In this case the construction may be simplified somewhat.

As the above detailed description is for the purpose of illustrating the invention, it will be understood that various modifications may be made without departing from the broader features of the invention.

Having described the invention, what I claim and desire to secure by Letters Patent is:

25 1. Apparatus of the type described which comprises, a tank, an inner wall in said tank spaced from the side wall of said tank to form an inner liquid storage compartment and an outer liquid seal compartment, said inner and outer compartments communicating at one edge of said inner wall, a bell extending over said inner wall and having its lower edge immersed in the liquid in said outer compartment, and means to maintain 30 a sufficient depth of liquid in said outer compartment to provide a seal for said bell in its normal rise and fall during the introduction and withdrawal of gas.

2. Apparatus of the type described which comprises, a tank, an inner wall in said tank spaced from the side wall of said tank to form an inner liquid storage compartment and an outer liquid seal compartment, means for displacing stored liquid in said storage compartment with water in emptying said compartment of stored liquid and for displacing said water with liquid to be stored in filling said compartment to hold the surface of sealing liquid in said outer compartment within narrow limits, and a bell extending over said inner wall and having its lower edge immersed in the liquid in said outer compartment.

3. Apparatus of the type described which comprises, a tank, an inner wall in said tank spaced from the side wall of said tank to form an inner liquid storage compartment and an outer liquid seal compartment, said inner and outer compartments communicating at the lower edge of said inner wall, a bell extending over said inner wall and having its lower edge immersed in the liquid in said outer compartment, means to maintain a sufficient depth of liquid in said outer compartment to provide a seal for said bell

in its normal rise and fall during the introduction and withdrawal of gas.

4. Apparatus of the type described which comprises, a tank, an inner wall in said tank spaced from the side wall of said tank to form an inner liquid storage compartment and an outer liquid seal compartment, said inner and outer compartments communicating at the lower edge of said inner wall, means for displacing stored liquid in said storage compartment with water in emptying said compartment of stored liquid and for displacing said water with liquid to be stored in filling said compartment, while maintaining the liquid surface in said outer compartment at a substantially constant level, and a bell extending over said inner wall and having its lower edge immersed in the liquid in said outer compartment.

5. Apparatus of the type described which comprises, a tank, an inner wall in said tank spaced from the side wall of said tank to form an inner liquid storage compartment and an outer liquid seal compartment, means for displacing stored liquid in said storage compartment with water in emptying said compartment of stored liquid and for displacing said water with liquid to be stored in filling said compartment, while maintaining the surface of liquid in said outer compartment at a substantially constant level, and means for enclosing the space above said inner compartment and sealing said means in said outer compartment.

6. Apparatus of the type described which comprises, a tank, an inner wall in said tank spaced from the side wall of said tank to form an inner liquid storage compartment and an outer liquid seal compartment, said inner and outer compartments communicating at one edge of said inner wall, means for supplying and withdrawing storage liquid and water from and to said tank, said means automatically withdrawing one of said liquids when its surface reaches a limiting level and a bell having its lower edge immersed in the liquid in said outer compartment.

7. Apparatus of the type described which comprises, a tank, an inner wall in said tank spaced from the side wall of said tank to form an inner liquid storage compartment and an outer liquid seal compartment, said inner and outer compartments communicating at the lower edge of said inner wall, means for supplying and withdrawing storage liquids and water from and to said tank, said means automatically withdrawing one of said liquids when its surface reaches a limiting level to maintain the surface of liquid in said outer compartment at a substantially constant level, and a bell having its lower edge immersed in the liquid in said outer compartment.

8. Apparatus of the type described which

comprises, a tank for liquids, an inner wall spaced from the side wall of said tank to form an inner liquid storage compartment and an outer liquid seal compartment communicating with said inner compartment at the bottom of said wall, a liquid inlet and overflow pipe for sealing liquid opening at the level of liquid in said outer space, a storage liquid inlet and overflow pipe communicating with the inner compartment and opening at the level of said storage liquid and a bell having its lower edge immersed in the liquid in the outer compartment.

9. Apparatus of the type described which comprises, a tank for liquids, an inner wall spaced from the side wall of said tank to form an inner liquid storage compartment and an outer liquid seal compartment communicating with said inner compartment at the bottom portion of said tank, a liquid inlet and outlet pipe for storage liquid communicating with said inner compartment, means for automatically withdrawing storage liquid when its surface reaches a definite level, means for withdrawing sealing liquid when its surface rises above a limiting level whereby the surface of said sealing liquid is maintained at a substantially constant level and a bell having its lower edge immersed in said sealing liquid.

10. Apparatus of the type described which comprises, a tank for liquids, an inner wall spaced from the side wall of said tank to form an inner storage liquid compartment and an outer sealing liquid compartment communicating with said inner compartment at the bottom of said tank, a liquid inlet and overflow pipe opening at the surface of said sealing liquid, a surrounding pipe for said inlet opening above and below the inner liquid level, an inlet and overflow in said inner compartment opening at the surface of said inner, storage liquid, and a bell having its lower edge immersed in said outer, sealing liquid.

11. Apparatus of the type described which comprises, a tank for liquids, an inner wall spaced from the side wall of said tank to form an inner storage liquid compartment and an outer sealing liquid compartment communicating with said inner compartment at the bottom of said tank, a liquid inlet and overflow pipe opening at the surface of said sealing liquid, a surrounding pipe for said inlet and overflow pipe opening above and below the upper and lower surfaces of said storage liquid respectively, an inlet and overflow pipe in said inner compartment opening at the surface of said inner, storage liquid, a bell having its lower edge immersed in said outer, sealing, liquid, and a water level gauge on said tank.

12. Apparatus of the type described which comprises, a tank having an inner compartment and an outer, surrounding,

compartment, means for placing said compartments in communication at a definite level below the normal liquid level of the outer compartment, a gas bell covering said inner compartment and sealed in the liquid of said outer compartment, and means for maintaining a sufficient depth of liquid in said outer compartment to provide a gas seal for the bell in its normal rise and fall during the introduction and withdrawal of substantial amounts of gas.

13. Apparatus of the type described which comprises, a tank having an inner compartment and an outer compartment, means for establishing a hydrostatic balance at a definite level between said compartments, means for filling said inner compartment with a liquid at levels other than said level of hydrostatic balance, a gas bell covering said inner compartment and sealed in the liquid in said outer compartment, and means for maintaining a sufficient depth of liquid in said outer compartment to provide a gas seal for the bell in its normal rise and fall during the introduction and withdrawal of substantial amounts of gas.

14. Apparatus of the type described which comprise, a tank having an inner compartment and an outer surrounding compartment, means for placing said compartments in communication at their lower levels, means for filling the inner compartment with a liquid lighter than water, means for maintaining liquid in said outer compartment at a substantially constant level, and a gas bell covering said inner compartment and sealed in the liquid of said outer compartment.

15. Apparatus of the type described which comprises, a tank having an inner storage compartment and a surrounding liquid seal compartment, a bell covering said inner compartment and sealed in said outer compartment, means for maintaining the liquid in said outer compartment at a substantially constant level, and means for maintaining the liquid pressure in the lower portion of said storage compartment substantially equal to the liquid pressure in the lower portion of said surrounding liquid seal compartment as stored liquid is withdrawn from, or supplied to said storage compartment.

16. A method of storing liquids which comprises, surrounding the liquid with a sealing liquid, enclosing the atmosphere above said liquid in a bell sealed in said surrounding sealing liquid, and displacing stored liquid with sealing liquid when withdrawing stored liquid and displacing sealing liquid with stored liquid when filling, to maintain the total volume of liquids approximately constant.

17. A method of storing volatile liquids

- which comprises, surrounding and supporting the stored liquid with a sealing liquid, displacing said sealing liquid downwardly in adding stored liquid and displacing said 5 storage liquid upwardly with sealing liquid in withdrawing said stored liquid to maintain the total volume of liquids approximately constant and enclosing the atmosphere above said storage liquid in a bell 10 sealed in said surrounding sealing liquid.
18. A method of storing liquids which comprises, surrounding the liquid with a sealing liquid, enclosing the atmosphere above said liquid in a bell sealed in said 15 surrounding sealing liquid, and displacing stored liquid with water when withdrawing stored liquid and displacing said water with stored liquid when filling, to maintain the total volume of liquids approximately 20 constant.
19. A method of storing volatile liquids which comprises surrounding the stored liquid with a sealing liquid, displacing said stored liquid upwardly with water when 25 withdrawing said stored liquid and displac-
- ing said water downwardly when adding stored liquid to maintain a substantial balance between the static head of the sealing liquid and the static head of the stored liquid and displacing water, and enclosing the 30 atmosphere above said stored liquid in a bell, sealed in said surrounding sealing liquid.
20. Apparatus of the type described which comprises a tank, an inner wall or 35 ring in the said tank spaced from the side wall of the tank to form an inner liquid storage compartment and an outer liquid sealed compartment, said inner and outer compartments being in communication, a 40 bell extending over said inner wall and having its edge immersed in the liquid of said outer compartment, and means for keeping liquid in said outer compartment being positioned within the ring and having its inlet 45 end opening adjacent the top of the ring.

In testimony whereof I affix my signature.

WILBUR G. LAIRD.
